INKING MECHANISM

Frederick Lamatsch, Grantwood, N. J., and Charles W. Ginsberg, Brooklyn, N. Y., assignors to R. Hoe & Co., Inc., New York, N. Y., a corporation of New York; Irving Trust Company, temporary trustee

Original application August 25, 1930, Serial No. 477,670. Divided and this application January 21, 1932, Serial No. 587,884

14 Claims. (Cl. 101—350)

This invention relates to improvements in inking mechanism for machines of the class used for printing newspapers and similar products, and is a division from our co-pending application, 5 Serial Number 477,670, filed August 25, 1930. It is the object of this invention to provide an improved form of ink distributing mechanism for printing machines that is simple, durable, positive and relatively inexpensive in construction, 10 as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in the precise embodiment of the invention herein disclosed may be made within the scope of what is 20 claimed without departing from the spirit of the invention.

The preferred embodiment of the invention is illustrated in the accompanying drawings, wherein:

25 Figure 1 is a side view of a portion of a printing machine, partly in diagrammatic form and partly in section, showing two printing units embodying our invention, and a folder to operate therewith is also indicated;

30 Figure 2 is an enlarged side view partly in diagrammatic form and partly in section showing a portion of one of the printing units;

Figure 3 is a detail view partly in section, showing means for operating the inking mechanism as it appears in the direction of arrow 3 of Figure 35 2; and

Figure 4 is a detail plan view partly in section, showing a portion of the means for operating the inking mechanism as it appears in the direction 40 of the arrow 4 of Figure 3.

Referring to Figure 1 of the drawings: 11 indicates the base frame of the printing machine. Two printing units are shown and designated respectively A and B. The side frames of the printing units are indicated at 12. Similar side frames are used on the opposite side of the machine, a portion of one of them being shown in Figure 3 and indicated as 12'. A folder of well known design is shown and indicated generally by the letter F.

The main driving shaft 14 is provided with bevel gears 15 that mesh with similar gears 16 on inclined shafts 17 and serve as a means to drive the printing units. Similarly, the mitre 55 gear 18 on the main shaft, meshes with the gear

19 on the shaft 21 and serves to drive the folding mechanism indicated generally as F.

The printing units each include a first or lower printing couple and a second or upper printing couple. The first printing couple has a form cylinder 34 and an impression cylinder 35, supported preferably in horizontal alignment and arranged to rotate in bearings carried in the frames 12 and 12'.

A first ink cylinder 36, a second ink cylinder 65 37, form rollers 38 and 39, transfer rollers 40 and 41 and distributing rollers 42, 43 and 44, are all likewise rotatably supported by bearings carried by the frames 12 and 12'. The printing cylinders of the second printing couple are oppositely arranged, and are indicated at 34' 70 and 35'.

The ink cylinders for the second couple are indicated at 36' and 37', form rollers at 38' and 39' and transfer rollers 40' and 41' and the distributing rollers at 42', 43' and 44'.

It will be noted that the form cylinder 34' is in vertical alignment with the impression cylinder 35 and the form cylinder 34 is in vertical alignment with the impression cylinder 35'.

Ink supplying mechanism is shown herein in the form of a pump device which is well known in the art and which provides separate ducts, each of which feeds ink to a separate section of the inking cylinder. The ink supply mechanism 85 for the first printing couple is indicated at 45, and that for the second printing couple at 45'.

The side frames 12 and 12' support an upper frame, partially shown in the drawings as 46, which carries guide rollers, bearings and turner bars, in accordance with usual practice to deliver the webs W and W' to the folder F.

Web guide rollers are provided in the printing units at 47, 48, and 49 by means of which the webs W and W' are led from suitable mechanism located on a level below the base frame of the printing machine to and through the printing units and thence around the guide rollers to the folder.

Web feeding plates or guides 51 and 51' are carried by suitable brackets attached to the frame of the machine and so arranged that when threading the end of the web through the machine, it may be placed on the feeding plates 105 and pushed forward into the bite of the printing cylinders, thus simplifying the operation of threading the web and avoiding danger of accident to the operator. The arrangement of guides of this kind is fully described in United States 110

Patent No. 1,613,960 granted to L. A. Schmidt on January 11, 1927.

The unit drive shafts 17 are supported in bearings formed in brackets secured to the side frame and indicated at 52, 53 and 54. The bevel gear indicated at 55 is secured to the shaft 17 and meshes with a similar gear that is connected with the impression cylinder 35. Similarly, the gear indicated at 55' is secured to the shaft 17 and meshes with a mitre gear secured to the impression cylinder 35'.

A step or platform indicated at 56 is preferably pivoted at 57 to brackets 58 secured to the frames 12 and 12' and is arranged at a convenient height to permit access to the upper form cylinder of the unit on which the platform is mounted, and also to the lower form cylinder of the adjacent unit. The arrangement of the cylinders in the frame, is such that the platform can be placed at a height not exceeding one step and still provide convenient access to the adjacent printing cylinders.

The preferred inking mechanism is shown in greater detail in Figures 2 and 3, and in addition to the parts previously described, includes mechanism for driving the ink cylinders and moving or vibrating them axially.

The impression cylinder 35 and the form cylinder 34 and likewise the impression cylinder 35' and the form cylinder 34' are geared together in pairs in the usual manner, and the shaft of the form cylinder 34' is extended as indicated in Figure 3 at 59, and a gear 61 is secured to it, and this is similarly true of the shaft of the form cylinder 34.

This gear 61 meshes with an idler gear 62 rotatably supported on a stud 63. The idler gear 62 meshes with a gear 64 that is secured to the shaft 65 of the inking cylinder 37'. Similarly, an idler gear 66 is rotatably supported on the stud 67 and meshes with the gear 64, and with a gear 68 that is secured to the shaft 69 of the ink cylinder 36'. Means are thus provided for rotating both ink cylinders in timed relation with the printing cylinders.

A gear housing and bracket indicated at 71, is secured to the side frame 12' and is fitted with bearings at several points indicated by the numeral 72, which serve to rotatably support a crank or vibrator shaft 73. The member 71 also serves to support one end of each of the studs 63 and 67, the opposite ends of which are secured in the frame 12'. A worm wheel 74 is secured to the crank shaft 73 and meshes with a worm 75 secured to the shaft 59 of the cylinder 34'.

The crank shaft 73 is formed with cranks 76 and 76', one of these being shown best in Figure 4, and these cranks may also be made as eccentrics if desired. Connecting rods or pitmen 77 are secured to wrist pins 78 that rotate in holes formed in lugs 78' that extend from the caps 79. The caps 79 are secured to swivel rings 81, which rotatably support the shafts 65 and 69. The assemblage including the caps 79 and the swivel rings 81 constitutes the preferred form of the mechanism hereinafter referred to as a swivel member.

It will be understood that a ball bearing indicated at 82 in Figure 4, serves as a thrust member and has its inner member secured to the shaft 65 by means of the nut 83 and the outer member of the ball bearing is secured in the swivel ring 81 by the cap 79, and this construction also applies to the other ink roller shaft 69.

The ball bearing which is of the deep groove type

is adapted to transmit axial thrust in either direction and the rotation of the crank or vibrator shaft 73 will thus result in moving or vibrating the shafts 65 and 69 forward and backward longitudinally in their bearings, while the inking cylinders will simultaneously be rotated through the gear train hereinbefore described.

Means for adjusting the impression contact between the form cylinders and the impression cylinders is provided by eccentric bushings 84 and 84' which form the bearings for the shafts of the form cylinders 34 and 34'. Segments 85 and 85' are secured respectively to bearing bushings 84 and 84' and have teeth which mesh with worms 86 and 86' having shafts 87 and 87' rotatably supported in brackets 88 and 88' secured to the side frames 12 and 12'. It will be understood that by rotating the shafts 87 and 87' that their respective form cylinders will be moved with relation to the cooperating impression cylinders and may be adjusted to obtain the requisite printing pressure. Cylinder adjustment mechanism of this kind is fully described in United States Patent No. 1,824,436 granted to F. Lamatsch on September 22, 1931.

The arrangement of the printing couples and the inking mechanism, in the frames of the machine is such that the ink distributing cylinders are within the space bounded by vertical lines tangent to the peripheries of their respective form cylinders, and the axes of the cylinders of the upper printing couple are in substantially vertical alignment with the axes of the printing cylinders of the lower couple and separated therefrom a distance not exceeding the width of the side frames of the machine. This arrangement permits free working space between the printing units and the printing cylinders are all accessible from operating platforms that are but one step higher than the floor level.

What we claim is:

1. In a printing machine, a cylindrical inking member secured to a shaft, a swivel member in axial alignment with and arranged to longitudinally move said shaft, the shaft being rotatable relatively to the swivel member, a crank shaft operably connected by the swivel member, and means to rotate the crank shaft.

2. In a printing machine, a cylindrical inking member secured to a shaft, a swivel member in axial alignment with and arranged to move the shaft longitudinally, the shaft being rotatable relatively to the swivel member, a crank shaft, a connecting rod connected to the crank shaft and to the swivel member, and means to rotate the crank shaft.

3. In a printing machine, a cylindrical rotatable inking member secured to a shaft, a swivel member in axial alignment with and adapted to move the inking member endwise, the shaft being rotatable with respect to the swivel member, a crank shaft, a connecting rod connected to the crank shaft and to the swivel member, and means to rotate the crank shaft.

4. An inking mechanism for a printing machine having a form cylinder, a first inking cylinder and a second inking cylinder, gearing adapted to rotate the inking cylinders in timed relation to the form cylinder, a vibrator shaft driven through gearing from the form cylinder, cranks 145 on the vibrator shaft, and connecting rods connecting the cranks to swivels connected to and in axial alignment with the inking cylinders.

5. In a printing unit for a multi-unit web printing machine, a printing couple including a 150

- form cylinder and an impression cylinder secured to rotatable shafts, inking mechanism including a first inking cylinder and a second inking cylinder secured respectively to shafts which are rotatable and movable axially, gearing adapted to rotate the ink cylinders in timed relation to the form cylinder, swivel members connected to the shafts of the ink cylinders, a vibrator crank shaft, pitmen connecting the cranks to the swivel members, a worm wheel on the vibrator shaft and a worm on the form cylinder shaft meshing with the worm wheel.
6. An inking mechanism comprising a rotatable cylinder mounted on a shaft, a swivel means in axial alignment with and secured to the shaft, and a pitman connecting said swivel means to a crank or eccentric on a rotatable vibrator shaft, said first mentioned shaft being rotatable within said swivel means.
7. In a printing machine, a printing cylinder, a worm gear in axial alignment with the cylinder and operably connected thereto, a drive shaft having a worm wheel adapted to engage the worm gear, a plurality of cylindrical inking members each secured to a supporting shaft and rotatable with respect to a swivel member arranged to move the supporting shaft longitudinally, eccentric driving connections on the drive shaft, and pitmen operably connected to the drive shaft and to each of the swivel members.
8. In a printing machine, a printing cylinder, a worm gear in axial alignment with the cylinder and operably connected thereto, a drive shaft having a worm wheel adapted to engage the worm gear, a plurality of cylindrical inking members each secured to a supporting shaft and rotatable with respect to a swivel member arranged to move the supporting shaft longitudinally, eccentric driving connections on the drive shaft, pitmen operably connected to the drive shaft and to each of the swivel members, and means for rotating said inking members in timed relation to the printing cylinder.
9. In an inking mechanism for a printing machine having a plurality of inking members, a corresponding plurality of shafts secured to the members, means to which said shafts are rotatably connected, a crank shaft, and elements pivotally connected to the crank shaft and hingedly connected to the said means, said first-mentioned means housing an instrumentality serving as a thrust member for an adjacent shaft of the said plurality of shafts.
10. In an inking mechanism for a printing machine, a plurality of vibrating inking members, a corresponding plurality of shafts secured to said members, each of said shafts being secured to and rotatable within thrust means, and a crank shaft arranged in angular relation to said shafts and having a plurality of cranks, each of said plurality of cranks having a swiveling connection to said thrust means.
11. In an inking mechanism for a printing machine, a frame, a plurality of vibrating inking members, a shaft attached to each of said members, a crank shaft mounted on said frame in angular relation to the plurality of shafts and having a plurality of cranks, thrust means surrounding the shaft of each of said inking members, and other means pivotally connected to each of said cranks and having a hinged connection to said thrust means.
12. In an inking mechanism for a printing machine, a plurality of vibrating inking members, a shaft secured to each of said members, a crank shaft arranged in transverse relation to the said shaft of each of the members, thrust assemblies arranged on and surrounding the end of each of said shafts, and a link hingedly connected to each of said thrust assemblies and to said crank shaft.
13. In an inking mechanism for a printing machine having a plurality of inking members, a corresponding plurality of shafts secured to the members, means connected to and permitting rotation of said shafts, a crank shaft, other means rotatably and hingedly connecting the said crank shaft to the first mentioned means, and thrust bearings arranged within a portion of the first mentioned means and directly engaged with each of said plurality of shafts.
14. In an inking mechanism for a printing machine having a plurality of inking members, a corresponding plurality of shafts secured to the members, means including apertured elements connected to and permitting rotation of said shafts, a crank shaft, links connecting the elements to the said crank shaft, and thrust bearings mounted on each of the plurality of shafts and arranged within the means.
